UNITED STATES PATENT OFFICE.

WILHELM R. LOHSE, OF MILWAUKEE, WISCONSIN, ASSIGNOR OF ONE-THIRD TO
NICHOLAS KOCH, OF MILWAUKEE, WISCONSIN, AND TWO-THIRDS TO GEORGE H.
CROWNS, OF PORT WASHINGTON, WISCONSIN.

BUTTERFLY-VALVE.

1,213,513.

Specification of Letters Patent. Patented Jan. 23, 1917.

Application filed May 8, 1916. Serial No. 95,026.

To all whom it may concern:

Be it known that I, WILHELM R. LOHSE, a subject of the Emperor of Germany, but having filed my intention to become a citizen of the United States, and resident of Milwaukee, in the county of Milwaukee and State of Wisconsin, have invented certain new and useful Improvements in Butterfly-Valves; and I do hereby declare that the following is a full, clear, and exact description thereof.

My invention refers to quick opening valves of the "butterfly" type, its primary object being to provide a simple, economical and effective control mechanism for the valve, whereby it is firmly and positively held in its seated position and is capable of a full opening movement by a half turn of the valve stem.

Another object of my invention is to provide the valve-actuating mechanism in such manner that when the valve is full open a straight passage through the valve shell is obtained without offering any material resistance to the flow of fluid therethrough.

Still another object of my invention is to provide means for locking the valve in any intermediate position from a point of leak to full open.

With the above and other minor objects in view the invention consists in certain peculiarities of construction and combination of parts as hereinafter set forth with reference to the accompanying illustrations and subsequently claimed.

In the drawings Figure 1 represents a sectional elevation of a valve embodying the features of my invention, the section being indicated by line 1-1 of Fig. 2 with the valve shown in its closed position; Fig. 2, a sectional view, as indicated by line 2-2 of Fig. 1, with the valve in its full open position, and Fig. 3, a detailed face view of a portion of the valve-locking mechanism.

Referring by characters to the drawings, 1 represents a valve housing provided with an inlet port 1' and a discharge port 1", each of the same being in alinement and the inlet port is provided with a straight valve seat 2. The valve housing is also provided with a cap closure 3 whereby the mechanism may be readily assembled and a gland 4 of standard type adapted to receive the valve stem 5 which extends transversely of the

housing ports and is stepped into a suitable bearing recess 4' opposite the gland. At the point of the stuffing-box or gland 4 the housing is extended to form a knurled hub 6, as best shown in Figs. 1 and 3. The indentures in the hub 6 are adapted to receive the spring plunger 7 which is carried by a valve-controlling handle 8, the same being suitably secured to the projecting end of the valve stem.

Mounted upon the valve stem 5 in alinement with the inlet opening is an eccentric 9, which eccentric is fitted into a circular aperture 10 of an ear 11, the said ear being extended from a valve disk 12. The ear is also provided with a circular slot 13 that communicates with the transverse circular aperture 10 therein, the said slot being extended through approximately 90°. The eccentric is secured to the valve stem by a key-pin 14, which pin is fitted into registered openings of the eccentric and stem. The head 13' of the key-pin projects beyond the eccentric and extends into the slot 13, being adapted to limit movement or play of the eccentric within the valve ear. By this arrangement it will be seen that the eccentric is not only held by the pin but serves as means for retaining the valve in its proper relation relative to the eccentric.

It will be observed that by the eccentric connection between the valve and stem when the stem is turned in one direction the valve will be forced to its seat, as indicated in dotted lines Fig. 2, in which position the full throw of the eccentric has not been completed. Hence a constant draw or pressure upon the valve can be maintained even though slight wear will result through continuous usage, the normal limit of movement of the outer-most portion of the eccentric lying in the dotted line X of Fig. 2 which passes through the axis of the valve stem. In this closed position the head 13' of the pin is at the opposite end of the slot to that shown in Fig. 2. When it is desired to open the valve the handle is revolved in the direction as indicated by the arrow in Fig. 2 and upon the initial movement of the handle the eccentric will cause the valve to lift from its seat. After the handle has made a quarter of a turn the head of the key-pin will have engaged the opposite end of the ear slot 13 and a further

quarter movement of the stem in the same direction will cause the valve to swing upon the axis of the stem to a full open position, as shown in Fig. 2. Hence it will be seen that the valve disk proper is approximately clear of the passage of water through the housing and the only obstruction offered to the straight flow is the width of the ear.

In actuating the valve in either direction by manipulating the handle 8 it will be observed that the spring plug 7 will not offer sufficient resistance to permit free movement of the stem and handle but when the handle is released the spring-pressed plug 15 7 will prevent displacement or movement of the stem, whereby the valve may be held in any position from a slight leak to full open.

In order to insure alinement of the disk with relation to the inlet opening, I provide the housing with a spur 15 which is positioned near the said inlet opening and is adapted to oppose the circular face of the valve when it is brought into approximate alinement with the aforesaid inlet opening. 25 Hence after it is partly seated by coming in contact with the spur further movement of the eccentric in a closing position will be exerted to force the valve firmly to its seat.

I have shown the valve disk 12 adapted 30 to receive a Jenkins disk 16 which is held in position by a suitable screw-confined washer 17. By this simple method the disk, when worn, can readily be replaced without incurring any expense except for the cost of 35 the standard disk mentioned.

I am aware that valves of this type have

been devised, but the actuating mechanism, so far as I am aware, of the prior art valves is such as to materially increase the cost of manufacture and, owing to the nicety of adjustments, the life of such valves in practice has been found to be short in comparison to their cost. With my valve structure the first cost of manufacture is reduced to a minimum as there is slight machine work 45 to be done and the assemblage can be effected by unskilled labor. The only point to be considered in assemblage is the positioning of the valve with relation to the eccentric and stem and when these parts are 50 properly positioned the headed key-pin is driven home, whereby all of the parts are confined.

I claim:

A valve of the butterfly type comprising 55 a housing having a port valve seat, a rotatable stem extending across the seat, a valve disk for the seat, an ear extending from the disk and provided with a circular aperture and a slot in connection with the aperture, 60 an eccentric head fitted on the valve stem and rotatably seated in the circular aperture, a locking pin extending through the eccentric head and stem, and said pin including a portion projecting into the slot of the ear 65 for limiting movement of the valve disk with relation to the stem eccentric.

In testimony that I claim the foregoing I have hereunto set my hand, at Milwaukee, 70 in the county of Milwaukee and State of Wisconsin.

WILHELM R. LOHSE.
